HANDLE SECURING STRUCTURE

Michael B. Andrie, Grand Rapids, Mich., assignor
to W. B. Jarvis Company, Grand Rapids, Mich.

Application July 12, 1937, Serial No. 153,161

12 Claims. (Cl. 70—350)

The main objects of this invention are:

First, to provide a novel and improved means for securing a door latch handle, window elevating handle, or other handle or lever to a shaft 5 or spindle associated therewith.

Second, to provide a structure of the type described wherein a handle may be quickly and readily assembled with its spindle or shaft and at the same time is effectively secured.

10 Third, to provide a structure of the type described wherein the securing means is entirely concealed.

Objects relating to details and economies of the invention will appear from the description to 15 follow. The invention is defined in the claims.

A structure embodying the features of the invention is illustrated in the accompanying drawing, in which:

Fig. 1 is a view partially in section illustrating 20 the improvements as applied to a door, the means operated from the spindle not being illustrated.

Fig. 2 is a fragmentary view partially in section of the handle and the cooperating spindle in disassembled relation.

25 Fig. 3 is a perspective view of the spindle.

The invention primarily relates to the assembling of door operating or window elevating or the like handles with their spindles or shafts, being particularly concerned with the hardware 30 of this type such as is commonly used on automobile doors and windows. It will be understood, however, that the scope of the invention is not limited in this respect and the provisions thereof may be adapted to a variety of fields or uses.

35 Referring to the accompanying drawing, the reference numeral 1 indicates a handle designed for operating a window and 2 its spindle. The spindle is associated with a suitable operating mechanism designated generally by the number 20.

The handle is provided with an escutcheon 3 secured to a door panel or the like 4. The handle is provided with a socket or recess 5 designed to receive the squared or otherwise non-circular 45 end 6 of the spindle 2. The cross section of the socket is such as to slidably receive the spindle and being conformed to its non-circular cross section, relative rotative movement of the two parts is prevented.

50 The recess has a small bore 7 at its inner end and in this recess I drive a suitable pin or screw 8, the threads 9 of which are preferably of relatively high pitch so that the threaded pin may be driven into the socket and cuts its own threads.

55 If preferred, the pin may be positioned in the

bottom of the socket by a casting with the handle thereon, the handles being commonly formed of die castings. The pin has hardened threads, this result being commonly secured by casehardening. When the pins are driven into position in the handle, the threads are substantially harder than the material of the handle. The pin is arranged so that a substantial portion thereof projects centrally into the socket. The pin is preferably tapered at its tip 10 to provide a pilot facilitating 10 its entry into the socket or bore 11 of the spindle 2.

The spindle is provided with an insert 12 which is arranged in the enlarged portion 13 of the bore of the spindle and secured therein by upsetting 15 or swaging the end of the spindle thereon as shown at 14, thus rotatably securing the insert or collar 12 in the spindle. This insert is in effect a nut blank and becomes a nut when the parts are assembled as will be hereinafter pointed out. 20 In assembling, the spindle is commonly mounted in the door or other part with which it is associated and in operative relation to the part which it is designed to operate.

The handle may at any stage in the manufacture of an automobile, for example, and after the upholstery indicated at 15 has been applied, be engaged with the spindle merely by slipping it upon the end of the spindle and driving it thereon. The pin engages the insert 12 and cuts or 30 threads its way into the same, the insert or collar rotating during this driving operation. When driven into place, the handle resists all ordinary strains or stresses to which it is subjected and is effectively retained. It may, however, be removed by a slow sufficiently strong pull without in any wise injuring the parts and without preventing its being replaced. It is the usual practice to secure handles of this kind by means of pins or set screws and these usually require accurate positioning of the handle relative to the spindle in order to bring the pin or key holes into 35 register.

While I have illustrated and described my improvements as embodied in a door or window operating handle, they may be readily embodied in valve handles and in many other relations. I have not attempted to illustrate or describe other embodiments or adaptations as it is believed that this disclosure will enable those skilled in the art 45 to embody or adapt my improvements as may be desired.

Having thus described my invention, what I claim as new and desire to secure by Letters Patent, is:

1. In combination, a spindle having a portion of non-circular section, a member having a recess corresponding in section to the non-circular section of the spindle and adapted to receive the same, and means for securing the spindle and member in assembled relation comprising an anchoring screw having relatively high pitched, hardened threads thereon, the recess in said member being counterbored and said screw being driven into the counterbore to thread itself substantially therein, said spindle having an axial recess, a cylindrical insert mounted adjacent the mouth of said spindle recess, said spindle being driven into the recess of said member with the screw engaging and threading itself into the insert during the driving operation, said insert rotating to permit said threading action, and means for retaining said insert in place adjacent said mouth.
2. In combination, a spindle, a member having a recess adapted to receive the spindle, means for securing the spindle and member in assembled relation comprising an anchoring screw having relatively high pitched, hardened threads thereon, the recess in said member being counterbored and said screw being driven into the counterbore to thread itself substantially therein, said spindle having an axial recess, a cylindrical insert mounted adjacent the mouth of said spindle recess, said spindle being driven into the recess of said member with the screw engaging and threading itself into the insert during the driving operation, said insert rotating to permit said threading action, and means for retaining said insert in place adjacent said mouth.
3. In combination, a spindle, a member having a recess, means for securing the spindle and member in assembled relation comprising an anchoring screw having relatively high pitched, hardened threads thereon, said screw being driven into the recess to thread itself substantially therein, said spindle having an axial recess, a cylindrical insert mounted adjacent the mouth of said spindle recess, said spindle being driven upon said screw with the screw engaging and threading itself into the insert during the driving operation, said insert rotating to permit said threading action, and means for retaining said insert in place adjacent said mouth.
4. Means for securing a handle to a spindle adapted to be rotated thereby comprising a hardened screw threaded element, said handle and spindle having recesses adapted to receive said element, said element being driven into the respective recesses, and means adjacent the mouth of one of said recesses for absorbing rotation incident to the threading action of said element during the driving operation of assembling the handle and spindle as specified.
5. Means for securing a handle to a member adapted to be actuated thereby comprising an element having hardened projections thereon, said handle and member having recesses adapted to receive said element, said element being driven into the respective recesses, and means adjacent the mouth of one of said recesses into which the projections are embedded during the driving operation of assembling the handle and spindle as specified.
6. Anchoring means for securing a handle to a spindle adapted to be rotated by the handle comprising a hardened screw threaded element, said handle and spindle having recesses adapted to receive said element, said element being driven into the respective recesses, and means adjacent the mouth of one of said recesses for absorbing rotation incident to the threading action of said element during the driving operation of assembling the handle and spindle as specified.
7. In combination, a handle, a spindle adapted to be actuated thereby, said handle and spindle having provisions for restraining the same from relative movement in assembled position, and means for locking the handle and spindle in assembled position, comprising an elongated element having relatively high pitch threads, said spindle having a recess adapted to receive the other end of the element and an insert adjacent the mouth of said spindle recess, said element being driven into said spindle recess with the threads thereof engaging said insert whereby to cause the material of the insert to flow and the element to thread itself therethrough, said insert being carried by said spindle for rotation relative thereto whereby the rotation resulting from said last named threading operation is imparted to said insert.
8. The combination of a spindle having a non-circular end portion and a shouldered longitudinal bore, a ring of relatively soft metal seated in the enlargement of said bore, the end of said spindle being upset upon said ring to rotatably retain the same within the spindle, and a handle having a non-circular socket receiving the non-circular end of said spindle and having an anchoring screw having hardened threads of relatively high pitch projecting from the bottom of its socket, said screw being provided with a tapered tip pilot portion, said handle and spindle being secured by driving them together whereby the screw enters the bore in the spindle and threads itself into the said ring therein.
9. The combination of a spindle having a non-circular end portion and a shouldered longitudinal bore, a ring of relatively soft metal seated in the enlargement of said bore, the end of said spindle being upset upon said ring to rotatably retain the same within the spindle, and a handle having a non-circular socket receiving the non-circular end of said spindle and having an anchoring screw having hardened threads of relatively high pitch projecting from the bottom of its socket, whereby the handle and spindle may be secured together by driving or forcing the spindle into the socket and the screw into the ring.
10. The combination of a spindle having a non-circular end portion, a ring rotatably retained within the spindle, and a handle having a non-circular socket receiving the non-circular end of said spindle and having an anchoring screw having threads of relatively high pitch projecting from the bottom of its socket, said handle and spindle being secured by driving them together whereby the screw threads itself into the said ring in the spindle.
11. In combination, a spindle, a member having an inwardly facing spindle receiving recess therein closed at the outer side of said member, and means for securing the spindle and member in assembled relation comprising an anchoring element having hardened projections thereon projecting from the bottom of the recess, said element being driven into the recess in said member to cause the element to be embedded substantially and non-rotatably supported therein, said spindle having an axial recess, said spindle being driven onto said anchoring element with the element being received in said spindle recess.
12. In combination, a handle having a spindle

recess of non-circular cross section, a spindle adapted to be actuated by said handle projecting into said handle recess and conformed in cross section thereto, and means for locking the handle and spindle in assembled position, comprising an elongated element non-rotatably mounted at the bottom of said handle recess and aligned

with said spindle, said element having hardened projections thereon and being secured to project into said recess in said handle, said spindle having a recess adapted to receive said element, said element being driven into said spindle recess. 5
